INVENTOR:
H. R. A. MALLOCK,
By his Attorneys,

Baldwin Wright

UNITED STATES PATENT OFFICE.

HENRY REGINALD ARNULPH MALLOCK, OF EXETER, ENGLAND, ASSIGNOR TO AMERICAN CELLULOSE AND CHEMICAL MANUFACTURING COMPANY LIMITED, A CORPORATION OF DELAWARE.

ROTARY PUMP.

Application filed February 6, 1922. Serial No. 534,616.

To all whom it may concern:

Be it known that I, HENRY REGINALD ARNULPH MALLOCK, F. R. S., a subject of the King of Great Britain, of Exeter, England, have invented certain new and useful Improvements in Rotary Pumps, of which the following is a specification.

This invention relates to pumps, more especially for use in spinning artificial threads from viscous solutions of cellulose acetate, viscose, nitrocellulose, cuprammonium cellulose or other cellulose derivatives, for the purpose of supplying the solution under pressure to the spinning jets or nozzles.

The invention concerns pumps of what is known as the gear type. These pumps, which are usually of small dimensions and run at low speeds, have been employed for supplying various liquids under pressure and their use for spinning artificial silk threads was proposed in British specification No. 28,320 of 1912. They comprise two toothed wheels gearing into each other and mounted in a casing in cells which closely envelop them while leaving an admission space or chamber on the unmeshing side and a delivery space or chamber on the meshing side of the wheels. One of the wheels is rotated by a spindle which passes out through the casing and is driven by toothed or chain gear or other mechanism, the spindle being usually supported in a bearing at its other or outer end. The solution, supplied to the pump from a reservoir or otherwise, enters and fills the admission space at the unmeshing side of the wheels and is carried round between the teeth of the wheels and the casing to the delivery space at the meshing side of the wheels, from which it is delivered through an outlet.

In spinning artificial silk it is of great importance to maintain the denier of the thread produced as uniform as possible, and consequently the pumps used for forcing the solution through the fine orifices of the spinning nozzles should deliver the solution very regularly and accurately.

In gear pumps as hitherto constructed and as employed for spinning artificial threads, the spindle that drives the driven gear wheel, i. e., the first toothed wheel of the pump, is either rigidly fixed thereto or is so disposed in relation thereto that the axes of

the spindle and of said wheel are constrained to parallelism during working.

We have found that very considerable irregularities in the denier of the thread produced arise in operation, on account of the difficulty in securing accurate coincidence between the true axis of the pump wheel, the axis of the driving spindle, and of the bearing which supports the driving spindle at its outer end. Any want of accuracy in these respects causes bending stresses in the pump which affect adversely the denier of the thread produced.

It has now been found that this drawback can be very greatly reduced and the pump rendered capable of useful employment for any purposes, and especially for making regular low deniers of artificial silk, by imparting the drive to the driver wheel of the pump through means which will allow the axis of the driving spindle to have angular play relatively to the axis of the said wheel, for example after the manner of a single Hooke's joint.

Any suitable means or device may be employed for the purpose referred to.

According to one form the driving spindle may be formed at the end with a ball from which projects radially a cylindrical stud, the ball fitting in a central circular hole cut in the toothed disc that forms the wheel, and the cylindrical stud fitting in a radial slot or keyway opening out of the central circular hole.

If desired, the other or outer end of the driving spindle may be supported by means which give no directional guidance to the axis of the spindle and are thus equivalent to a second Hooke's joint. Such means might consist of a simple hole in a plate into or through which the outer end of the spindle carrying the toothed or chain wheel or the like passes, the spindle having, or not, a spherical or like portion working in the hole. Preferably, however, when a second device of Hooke's joint character is employed, this is made so that the driving spindle is independent of or separable from

the axis of the toothed or chain wheel or other device that imparts the drive to the driving spindle, so that the pump can be dismounted without removing this wheel or device. For example the outer end of the driving spindle may be formed with a ball

end projecting into an elongated axial cylindrical socket or boss of the toothed or chain wheel or the like, which is mounted in a bearing or support, the ball end having a 5 projecting cylindrical stud engaging in a groove or slot cut in the said socket or boss. Thus the driving spindle can be withdrawn from the socket or boss when required without dismounting the toothed or chain wheel 10 or the like that imparts the drive to it. A coiled spring may be fitted in the socket or boss to assist in keeping the driving spindle with its other end in good engagement with the gear wheel of the pump. Any other 15 connection of a Hooke joint character may of course be employed.

The second wheel of the pump is preferably in the form of a toothed disc simply fitted accurately in its closely embracing cell 20 in the casing and the toothed wheels of the pump or their circumferences are preferably ground to the walls of their cells in the casing.

The accompanying drawings illustrate by 25 way of example a gear wheel pump constructed and arranged in accordance with the invention in one form thereof, Fig. 1 being a side elevation, partly in vertical mid-section, of the pump and driving gear, 30 and Fig. 2 a sectional view of the pump with the outer plate or cover 3 removed.

The pump comprises as usual three plates or sections 1, 2, 3 of steel or other suitable metal fixed tightly together by screws 5 passed through holes 6 in the sections 1 and 2 and screwing into tapped holes registering therewith in the cover or section 3, the middle section 2 being formed accurately with the holes that form the chambers or 40 cells closely surrounding the gear wheels 7, 8 and leaving a small inlet chamber 9 on the unmeshing side of the wheels and a discharge chamber 10 on the meshing side. 11 indicates the supply passage leading to the 45 inlet chamber 9, and 12 the delivery passage leading from the discharge chamber 10. Lugs 13 on the section 1 provide for bolting the pump to a suitable part of the spinning metier as usual.

50 As shown in Figs. 1 and 2 the second or follower wheel 8 of the pump is in the form of a toothed disc simply fitted in its cell.

14 is the driving spindle of the pump projecting through a hole 15 in the cover of 55 the pump and formed at this end with a ball 16 from which a cylindrical stud 17 projects radially, the ball 16 fitting in a central circular hole cut in the toothed wheel 7 of the pump, and the stud 17 fitting in a radial slot or keyway 18 opening out of the central hole of the wheel. Thus the drive can 60 be imparted to the gear wheel 7 while allowing the axis of the driving spindle 14 to have angular play relatively to the axis of this 65 wheel.

The outer end of the driving spindle 14 is formed with a ball end 19 projecting into an elongated axial socket or boss 20 of the chain wheel 21 that drives the pump, this wheel being mounted in a pillar bearing 22 70 mounted on the spinning metier in any suitable way. The ball end 19 has a cylindrical stud 23 engaging in a slot 24 cut in the socket or boss 20. Thus while the outer end of the driving spindle does not receive directional guidance from the hollow boss 20, it can be withdrawn therefrom when required, without dismounting the chain wheel 21, 25 is a coiled spring fitted in the hollow boss 20 to assist in keeping the driving spindle 14 80 with its other end in good engagement with the gear wheel 7 of the pump.

What I claim and desire to secure by Letters Patent is:—

1. In a pump apparatus of the gear type 85 comprising intermeshing driver and driven liquid forwarding gear wheels located in the pump casing, the combination of a driving spindle for the driver gear wheel and a pivotal driving connection between said 90 spindle and the driver gear wheel, whereby the axis of said spindle has angular play relatively to the axis of the driver gear wheel.

2. In a pump apparatus of the gear type 95 comprising intermeshing driver and driven liquid forwarding gear wheels located in the pump casing, the combination of a driving spindle for the driver gear wheel, a pivotal driving connection between said spindle and the driver gear wheel, whereby 100 the axis of said spindle has angular play relatively to the axis of the driver gear wheel, means for freely supporting the outer end of the driving spindle, said means giving no directional guidance to the spindle 105 axis, and means for imparting rotation to said driving spindle.

3. In a pump apparatus of the gear type 110 comprising intermeshing driver and driven liquid forwarding gear wheels located in the pump casing, the combination of a driving spindle for the driver gear wheel, a pivotal driving connection between said spindle and the driver gear wheel, said connection comprising a central hole in the driver gear 115 wheel, a radial slot opening therefrom and a ball end on said spindle fitting in said central hole and having a stud engaging in said radial slot.

4. In a pump apparatus of the gear type 120 comprising intermeshing driver and driven liquid forwarding gear wheels located in the pump casing, the combination of a driving spindle for the driver gear wheel, a pivotal driving connection between said spindle and the driver gear wheel, whereby the axis of 125 said spindle has angular play relatively to the axis of the driver gear wheel, a wheel for imparting rotation to said driving spindle, an axial socket on said wheel 130

adapted to receive the outer end of said driving spindle, a pivotal driving connection between said socket and the outer end of the driving spindle, comprising an open ended longitudinal slot in said socket, and a stud on the outer end of said driving spindle and engaging in said open ended slot, whereby the outer end of the driving spindle is freely supported without directional guidance of the spindle axis.

5. In a pump apparatus of the gear type comprising intermeshing driver and driven liquid forwarding gear wheels located in the pump casing, the combination of a driving spindle for the driver gear wheel, a central hole in the driver gear wheel, a radial slot opening therefrom, a ball end

on said spindle fitting in said central hole and having a stud engaging in said radial slot, a wheel for imparting rotation to said driving spindle, an axial socket on said wheel adapted to receive the outer end of said driving spindle, an open ended longitudinal slot in said axial socket, a spherical portion on the outer end of the driving 25 spindle engaging in said socket, a stud on said spherical portion engaging in said open ended slot, and a spring located between the outer end of the driving spindle and the bottom of the axial socket.
